UNITED STATES PATENT OFFICE.

OTTO FRANCK, OF PHILADELPHIA, PENNSYLVANIA.

DOORSTOP.

Continuation of application Serial No. 504,954, filed October 3, 1921. This application filed February 6, 1922. Serial No. 534,560.

To all whom it may concern:

Be it known that I, OTTO FRANCK, a citizen of the United States, residing at Philadelphia, county of Philadelphia, and State 5 of Pennsylvania, have invented certain new and useful Improvements in Doorstops, of which the following is a specification.

My invention relates to door stops, that is, to devices for holding a door in open 10 position; and the present application is a continuation of my application Serial No. 504,954.

The object of my invention is to provide a simple device that may be readily attached to a floor in the path of the outer 15 or free edge of the door and which, when contacted by said door, will automatically operate to lock the door in open position. A further object of my invention is to provide 20 a device of the character mentioned, which may be readily operated by the foot or otherwise, to release the door. A further object of my invention is to provide a device of the character mentioned which 25 will be adapted for use in conjunction with either right or left hand doors, that is, with doors hinged at either the right or left side thereof. A further object of my invention is to provide means for maintaining the device 30 in operative position. Further objects of my invention are to provide a device as mentioned which shall be of simple construction, and which may be readily applied by practically any one without requiring 35 the services of a mechanic. Other objects will appear hereinafter.

With these objects in view my invention consists generally in an arm or lever adapted to be pivotally mounted at one end thereof to the floor adjacent the path of the outer edge of a door, and provided with lateral 40 projections adapted to embrace the edge of the door between them, one of said projections being arranged adjacent the pivot and adapted to be contacted by the door to move the arm or lever into operative position. My invention further consists in a device as mentioned further characterized by a longitudinally 45 extending projection or lug 45 forming a toe-piece by means of which the device may be moved to release the door. My invention further consists in a device as mentioned further characterized by a shield 50 adjacent said toe-piece to prevent the shoe from coming in contact with or catching

under the door. My invention further consists in providing a device as mentioned further characterized by having the lateral projections on both sides of the arm or lever whereby the device may be adapted for use 60 in conjunction with doors hinged either upon the right or left side. My invention further consists in a device as mentioned further characterized by means for limiting the movement of the device so as to 65 maintain it in operative position. My invention further consists in various details of construction and arrangements of parts all as will be fully described hereinafter and particularly pointed out in the claims. 70

My invention will be more readily understood by reference to the accompanying drawings forming a part of this specification, and in which—

Fig. 1 is a plan view of a door stop embodying my invention, a portion of a co-operating door being illustrated in conjunction therewith. 75

Fig. 2 is a side elevation of the device, and Fig. 3 is an end elevation of the same. 80

Referring now to the drawings, 1 indicates an arm adapted to be pivotally connected to the floor at one end, as by a screw 2. The pivot end comprises a substantially vertical portion 3 which projects upwardly 85 from the floor a considerable distance for a purpose hereinafter described. Preferably the major part of the portion 3 is cut away as indicated at 4 to reduce the thickness for the reception of the screw 2, thereby by lessening the quantity of metal required and also considerably lessening the boring or drilling of the aperture 5 for the screw 2. 90

The arm 1 extends outwardly from the upper portion of the part 3 and curves downwardly, as at 6, at its outer end, terminating in lateral extending lugs 7 upon the ends of which are depending feet 8. Projecting laterally from the upper end of the portion 3 are lugs 9 between which and the lug 7, the 100 edges of the door 10 is adapted to be held. The lugs 9 constitute stops for the door when opening, and also when engaged by the door, causes the arm 1 and lugs 7 to swing into operative position to secure the door. By 105 having the portion 3 of considerable height and arranging the lugs 9 at the upper end thereof, the door will be sure to engage the same even though it swings at quite a distance above the floor. Projecting longitudi- 110

2
nally from the end of the arm 1 is a toe-piece 11 by means of which the device may be moved to inoperative position to release the door. In order to prevent the operator 5 from catching the toe of his shoe under the door, should the same be at a sufficient distance above the floor, or from catching it under the arm 1, I provide the shield 12. This also prevents the forward portion of the de- 10 vice from becoming wedged under the door, when the latter swings high enough from the floor to permit it.

To prevent the device from being turned into a position where it will not be properly 15 operated upon by the door, I provide lugs 13 projecting from the base of the portion 3 and between these lugs I arrange a stop 14, such as a screw secured to the floor. It is obvious that the stop may be of any preferred form. 20 The lugs 13 are spaced apart a proper distance to permit sufficient swinging of the device but to maintain the same at all times in operative position, that is, in a position where the lug 9 will be engaged by the door.

25 It will be noted that the device is identical at both sides so that the device may be adapted for use in conjunction with doors that are hinged either upon the right or left side. The operation of the device is obvious.

30 I claim:

1. A door stop comprising a vertical portion, an arm extending outwardly and downwardly from the upper portion thereof, lateral projecting lugs adjacent the ends of 35 said arm, and means adjacent said vertical portion for pivotally connecting the device to a floor, substantially as described.

2. A door stop comprising an arm and means at one end of the arm for pivotally

connecting the same to a floor, and integral 40 projecting lugs on said arm adapted to embrace the edge of the door, said lugs projecting laterally from both sides of said arm as and for the purpose specified.

3. A device as set forth in claim 1 further 45 characterized by a longitudinal extending toe-piece, substantially as described.

4. A device as set forth in claim 1 further characterized by a longitudinal extending toe-piece and a shield on said arm adjacent 50 said toe-piece, substantially as described.

5. A door stop comprising a vertical portion, an arm extending outwardly and downwardly from the upper end thereof, lateral 55 extending lugs at the lower end of the said arm, the ends of the said lugs terminating in downwardly extending feet, and laterally extending lugs on said vertical portion and means adjacent said vertical portion for pivotally connecting the device to a floor, substantially as described.

6. A device as set forth in claim 5 in conjunction with a longitudinal extending toe-piece, and an upwardly curved shield adjacent thereto, substantially as described.

7. A device as set forth in claim 2 further characterized by a pair of spaced lugs projecting from said vertical portion and a stop member adapted to be positioned between said lugs as and for the purpose specified.

In testimony whereof I have signed my name to this specification in the presence of two subscribing witnesses.

OTTO FRANCK.
